UNITED STATES PATENT OFFICE.

ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

AUTOMATICALLY-THREADING LOOM SHUTTLE.

1,405,452.

Specification of Letters Patent. Patented Feb. 7, 1922.

Application filed September 2, 1921. Serial No. 497,844.

To all whom it may concern:

Be it known that I, ISAAC SNOW, a citizen of the United States, residing at Lawrence, in the county of Essex and State of Massachusetts, have invented an Improvement in Automatically-Threading Loom Shuttles, of which the following description, in connection with the accompanying drawings, is a specification, like characters 10 on the drawings representing like parts.

This invention relates to automatically threading loom shuttles which are used in looms wherein the weft or filling is automatically replenished from time to time. In 15 looms of this type, the filling or weft carriers are located in a magazine, and the ends of the threads are secured to a holder. When a carrier is inserted into the shuttle during the operation of the loom, and the 20 shuttle is picked for the first time across the lay, the thread is drawn from the filling carrier within the shuttle and the shuttle becomes preliminarily or partially threaded. On the return trip of the shuttle 25 the thread is fully threaded so that the thread then leads from the side delivery eye.

In the subsequent operation of the loom, and owing to the sudden stop of the shuttle at the end of each pick, the thread which is 30 withdrawn from the filling carrier is liable to be overthrown from the shuttle and form a loop which in many cases either effects an unthreading of the loom shuttle or breaks the thread on the following pick.

35 An important feature of the present invention, therefore, consists of a thresher for loom shuttles which shall be reliable and effective in threading the shuttle and thereafter during the operation of the loom, shall 40 prevent unthreading or breaking of the thread.

These characteristics of the invention and other novel features and combinations of parts will best be made clear from the following description and accompanying drawings which show one good, practical form 45 of the invention, wherein:

Figure 1 is a top or plan view of the threading end portion of the shuttle provided with the present invention;

Figure 2 is an enlarged perspective view of the automatic thresher;

Figure 3 is an end view of the thresher, substantially on the same scale as Fig. 2,

and looking from the bobbin chamber toward the rear end of the thresher;

Figure 4 is an end view of the thresher looking from the front or leading end and at one side of the longitudinal center of the thresher; and

Figure 5 is a side elevation of the thresher, showing more particularly the thread rest, the thread retaining hooks, and the thread guard which extends upwardly into the space between the hooks.

The shuttle 1 is provided with the bobbin chamber 2 in which is held the bobbin or filling carrier 3, as usual. The leading or front end portion of the shuttle has the thread receiving passage 4 which is inclined 70 downwardly toward the thread passage of the thresher. The thread receiving passage 4 receives the standing portion of the thread *a*, as indicated by dotted lines in Fig. 1, when the shuttle is first picked after a replenishing operation, and serves to permit the thread to pass into the control of the thresher. Extending laterally from the thread-receiving passage is the usual guide slot 5 which leads to the side delivery eye 80 6 formed in the wood of the shuttle. The parts thus far described are or may be of usual construction.

The automatic thresher is shown as formed of a single piece or casting which 85 may be advantageously employed in the construction of the thresher; but it is not intended to circumscribe the invention by having the thresher formed of a single casting or piece.

As shown, the thresher 7 has a longitudinally-extending thread passage 8 and a thread directing top guide 9, the surface of which, as best indicated in Fig. 4, curves from the top portion or surface of the 95 shuttle downwardly toward the opposite side of the shuttle and overlies the thread passage 8. At the leading end portion of the thresher is the horn 10 which has the downwardly-inclined edge portion 11 for directing the thread downwardly and under the recess or guide 12, from which point the thread leads to the side delivery eye.

In the present instance of the invention the thresher is provided with a pin or post 105 13, the end of which preferably seats in the wood of the shuttle and about the post 13 the thread draws as it changes direction

from the thread passage to the side delivery eye, as best indicated in Fig. 1. Where the threader is formed of a single block or casting, as shown, it may be provided with the 5 projection 14 adapted to be seated in a suitable opening in the wood of the shuttle to assist in holding the threader in its proper relation with the shuttle body. A transversely extending opening 15 may be formed 10 in the threader for the reception of a securing bolt 16, as indicated in Fig. 1, the construction being such that when the threader is in place in the cavity formed for its reception in the wood of the shuttle, the projection 14 and the securing bolt 16 serve in connection with the wood of the shuttle to hold 15 the threader in place. The parts thus far described may be of usual construction, and as shown are well adapted for cooperative 20 relation with the main features of the present invention.

Extending at one side of the thread passage 8 is a thread rest 17, on which the standing part of the thread α (see dotted 25 lines, Fig. 1) may rest as the thread is drawn from the shuttle on the first pick following replenishment. The thread rest 17 is preferably inclined downwardly from the leading or delivery end of the threader toward the entrance of the thread passage 8, as best indicated in Figs. 2 and 5, the inclination of the rest being preferably such 30 that the thread rest 17 merges into the incline surface of the thread-receiving passage 4 without abruptness.

The thread directing top guide 9 has a 35 downwardly curved edge portion 18 which overlies the thread rest 17 more or less, and is inclined to the longitudinal axis of the shuttle, the inclination being such that the portion of the thread directing top guide adjacent the bobbin chamber is closer to the opposite wall of the shuttle than is the leading end of the top guide, as indicated in 40 Fig. 1.

The thread directing top guide 9 is provided with two thread retaining hooks 19 and 20, the leading hook 19 being pointed 45 toward the bobbin chamber while the hook 20 is pointed in the opposite direction or toward the adjacent end of the shuttle. The two hooks may be generally similar except that they point in opposite directions, but in the present instance of the invention the hook 20 has its end portion 21 inturned in 50 order to facilitate the entrance of the thread into the thread passage, as will presently appear, and further to prevent the thread from being thrown from the thread passage 55 during the flight of the shuttle.

The thread retaining hooks 19 and 20 are 60 shown as formed integral with and extending downwardly from the thread directing top guide 9 toward the thread rest 17. The 65 edge portions 22 and 23 of the thread retain-

ing hooks are separated a slight distance from the surface of the thread rest 17 and provide a thread side passage for the entrance of the thread from the thread rest laterally into the thread passage. The 70 downturned or curved portion 24 between the two hooks 19 and 20 is cut away to form a space between the hooks, and an enlarged portion of the thread side passage between the hooks. This may not always be necessary, but as the yarn swirls during the un-winding operation, due to the flight of the shuttle on the first pick after replenishment, the enlarged opening thus provided gives 75 greater assurance of the entrance of the thread from the thread rest through the thread side passage into the thread passage of the threader.

The surface or edge portion 25 of the hook 20 adjacent the entrance end of the thread 80 passage is preferably curved frontwardly or turned toward the end of the shuttle as indicated in Fig. 5, in order to cast any loop that may be formed about the hook 20 during the weaving operation.

As more clearly indicated in Fig. 1, it will be noted that the thread retaining hooks 19 and 20 project in a gradually curved direction downwardly toward the thread rest without obstructing the free entrance of the 90 thread between the edge 18 of the thread directing top guide and the opposite side wall 26 of the shuttle. By this construction the thread is given free and unobstructed access to the thread rest during the first 100 flight of the shuttle after replenishment and is supported for entrance through the thread side passage into the thread passage 8.

Extending upwardly from the thread rest 17 is the guard 27 which projects into the 105 space between the hooks 19 and 20, the construction being such that after the thread has passed through the thread side passage leading to the thread passage 8, it will be effectively prevented from escaping from 110 the thread passage in the opposite direction during weaving.

As shown, the guard 27 is extended upwardly from the thread rest 17 and is formed integral therewith, but obviously this is not 115 always essential, the essential being that it extend upwardly into the space between the hooks to perform its described function.

When the thread finds its seat on the thread rest 17 and is being swirled by the withdrawal of the thread from the shuttle, it is desirable that the thread be directed through the thread side passage over the top of the guard 27, and to this end the outer surface portion of the guard as at 28, is upwardly 120 curved or rounded from the thread rest 17, so that the thread will readily be guided upwardly upon and over the top of the thread guard 27.

The leading end portion of the thread rest 125

17, that is, the end nearer the tip of the shuttle, is preferably made wider than the end of the rest adjacent the entrance to the thread passage, and while this is found to be advantageous in practice, it may not always be necessary.

Where the thread rest 17 is inclined downwardly toward the bobbin chamber as shown, the hooks 19 and 20 extend different distances from the thread directing top guide 9, the construction being such that the thread side passage may be formed substantially as indicated in Fig. 5, wherein the distance between the surface of the thread rest 17 and the adjacent surfaces of the two hooks 19 and 20 are substantially the same, and such edges of the hooks preferably overlie the adjacent edge portion of the thread rest next to the thread passage.

When the shuttle is first picked after a replenishing operation, the thread drawn from the shuttle takes position substantially as indicated by dotted lines *a*, Fig. 1, wherein it will be noted that the thread extends over and rests upon the thread rest 17 and upon the surface of the thread receiving passage 4; and as the shuttle proceeds to the opposite side of the loom, and the thread is unwound from the filling carrier or bobbin, the swirl action of the thread carries the part that rests upon the thread rest through the thread side passage into the thread passage 8, the directing surface 28 acting at such times to direct the bight of thread up over and beyond the guard 27. On the next pick of the shuttle, the thread *a* will be held by the opposite selvage and will thereupon be drawn through the passage 5 into the side delivery eye 6. The shuttle is then completely threaded. During the weaving operation, the guard 27 which extends into the space between the hooks 19 and 20 effectively prevents unthreading of the shuttle. If, by any chance, the thread should leave the side delivery eye and pass beyond one of the hooks 19 or 20, the other hook will serve to maintain the thread in the threader without breaking, so that on the succeeding picks of the shuttle, the thread will again be finally drawn into the side delivery eye.

What is claimed is:

1. An automatically threading shuttle, having, in combination, a side delivery eye, a threader having a thread passage communicating with the side delivery eye, a thread rest at one side of the thread passage inclined downwardly toward the bobbin chamber, a thread directing top guide having downwardly extending thread retaining hooks which form a thread side entrance from the thread rest to the thread passage, and a guard extending upwardly from the thread rest into the space between

the hooks and obstructing the thread side entrance.

2. A threader for automatically threading loom shuttles having a longitudinally extending thread passage, an inclined rest at one side of the thread passage and communicating therewith, two hooks extended downwardly from the top of the threader different distances toward the thread rest and forming a thread side passage between the thread rest and adjacent portions of the hooks, and a guard extended upwardly from the thread rest into the space between the hooks.

3. A threader for automatically threading loom shuttles having longitudinally extending thread passage, a thread directing top guide having two downwardly extended hooks forming a side entrance to the thread passage, and a guard extending upwardly into the space between the downwardly extended hooks.

4. An automatically threading shuttle having, in combination, a thread receiving depression and a side delivery eye, a threader having a longitudinally-extending thread passage communicating with the side delivery eye, thread retaining hooks extending in opposite directions at one side of the thread passage, and a guard extending upwardly from the lower portion of the threader into the space between the thread retaining hooks.

5. An automatically threading shuttle having, in combination, a side delivery eye, a threader having a longitudinally extending thread passage communicating with the side delivery eye, a thread rest at one side of the thread passage, thread retaining hooks which extend downwardly from the top guide of the threader toward the thread rest, and a thread guard extending upwardly adjacent the side entrance to the thread passage into the space between the thread retaining hooks.

6. A threader for automatically threading loom shuttles having a longitudinal thread passage, a thread rest at one side of and communicating with the thread passage, two hooks extended downwardly from the top of the block toward the thread rest with a space between them, and a guard extended upwardly from the thread rest into the space between the hooks.

7. An automatically threading loom shuttle, having, in combination, a side delivery eye, a threader having a thread passage communicating with the side delivery eye, a thread directing top guide, two thread retaining hooks pointing in opposite directions with a space between them and forming a thread side entrance to the thread passage, and a combined thread director

and guard extending into the space between the thread retaining hooks and having an outer thread directing surface for directing the thread through the thread side entrance to the thread passage as the thread is withdrawn from the shuttle.

8. A threader for loom shuttles having a longitudinally extending thread passage, a thread directing top guide, a thread rest at one side of the thread passage, thread retaining hooks which extend downwardly toward the thread rest and form a thread side entrance between the thread rest and hooks, and a combined thread director and guard 15 extended from the thread rest into the space between the retaining hooks.

9. A threader for automatically threading loom shuttles having a thread passage, a thread rest at one side of the thread passage and inclined downwardly toward the 20 entrance to the thread passage, a thread directing top guide, two thread retaining hooks extended downwardly toward the inclined thread rest amounts determined by the inclination of the thread rest and forming in connection therewith a thread side entrance, and a guard extended upwardly from the inclined thread rest into the space between the hooks. 25

In testimony whereof, I have signed my name to this specification.

ISAAC SNOW.
